LEAD-IN CONDUCTOR FOR MERCURY
VAPOR TUBES

Franz Lauster, Hanau-on-the-Main, Germany

Application November 4, 1936, Serial No. 109,177

1 Claim. (Cl. 176—126)

In high pressure mercury vapor tubes, as is known, the output of radiation increases as the specific load of the discharge is increased. An object of this invention is to provide a lead-in conductor for tubes adapted to carry high current loads.

This high current load necessitates that all dead spaces which might act as condensation points for the mercury vapor be avoided. The familiar tungsten wire leads, which are fused into quartz by using a single transition glass, avoid dead spaces but can only carry a low current load and are therefore unsuitable. In the present invention metal foils of less than 0.02 mm. thickness are used as current leads. Such foils can be fused directly into the quartz tube and can carry current loads up to ten amperes. Thus a high order of radiation output is obtained with tubes made according to this invention and a satisfactory operating life is achieved at the same time owing to the comparatively low vapor pressure developed.

With high pressure mercury vapor tubes there is a danger that part of the mercury required for operation may condense in the pole chambers, where the temperature is considerably lower than in the remainder of the tube. To prevent such condensation, the wall thickness of the pole chambers is made greater than that of the remainder of the tube, thereby increasing the temperature on the inner walls of the pole chambers. As a further precaution the section of the tube available to the arc may be constricted in the vicinity of the pole chambers.

In some cases the enlargement of the wall thickness may be limited by the external or the internal diameter of the pole chambers. In this event, the pole chambers may be screened off from the remainder of the tube by means of flanges which will cause more electrical energy to be converted into heat in the pole chambers. The provision of constrictions and/or flanges as such is known, but these have hitherto been employed for different reasons. It is only when tubes, according to the invention, develop vapor pressures in excess of five atmospheres that a constriction in the vicinity of the pole chambers will produce any considerable increase in the potential gradients with the accompanying conversion into heat within the pole chambers.

In the accompanying drawing, Fig. 1 is a somewhat diagrammatic longitudinal sectional view of a high pressure mercury vapor tube according to the invention. Fig. 2 is a sectional view on the line II—II of Fig. 1, of an end portion of the tube

showing the lead-in foil. Fig. 3 is a perspective view of part of a lead-in foil and part of an electrode connected therewith. Fig. 4 is a perspective view similar to Fig. 3 of a modified embodiment of the lead-in foil and electrode. The tube 1 consists of quartz. The arc tube portion 2 is screened off from the pole chambers 5 and 6 by means of flanges 3 and 4. The thermionic electrodes 7 and 8 can, for example, consist of tungsten wire wound round a thicker tungsten wire, or other metals with high melting points may be used to advantage in some circumstances. Substances having a low work function, e. g. alkaline earth oxides, are applied to the electrodes in known manner, the electrodes preferably being heated to the necessary incandescence by the discharge itself. On the thick tungsten wires are fastened metal foils 9 and 10 which are fused into quartz capillaries of suitable section to form a high vacuum-tight seal. In doing this, it is advantageous to lay the ends of the tungsten wires in a fold of the foil so as to obtain a good electrical contact with the drawing 11 of the quartz. The foils are protected against the discharge if, as shown in the illustration, the ends of the pole chambers have an opening only exactly sufficient for the passage of the tungsten wires. The metallic lead in foils are made of a refractory metal such as tungsten or molybdenum and, of a width of about 3 to 5 mm., are of a thickness which is less than 0.02 mm. and preferably less than 0.01 mm. Such thin foils can be fused directly into the quartz. They form a completely vacuum tight seal, requiring no further sealing means. The outer current leads may not be connected directly to these foils since the latter are not of great mechanical strength and, moreover, are often damaged where they are not embedded in quartz, by oxidation during operation. It is, therefore, necessary to attach a strong wire to these foils and to connect the external current leads thereto. As shown on the drawing, this is done by folding the foils over once and placing the wire between the foils. The foils may be penetrated at the folds so that the connector wire is positioned axially, as shown by the drawing. Current connection to the electrodes is accomplished in similar manner. The connection between the foils and the wire may be effected by welding, if desired. In general, however, welding is not necessary. The fusing of the foils into the quartz must be carried out in vacuum. It is, therefore, convenient to place the foils and the folded-in connector wires in a quartz tube having a suitable inside diameter and to evacuate the in-

terior thereof. After softening of the quartz, the quartz tube is completely pressed together by means of external air pressure so that it is in direct contact throughout with the foil, including the folded parts. Upon cooling of the quartz, the rigid material encompassing the foil prevents the connection from becoming loose. This joint is thus adequate even for large currents. To avoid condensation of the mercury, the wall 12 of the 10 pole chambers 5 and 6 is made thicker than the wall 11 of the arc tube 2. Owing to the greater fall of temperature within the walls of the pole chambers, even the smaller transformation of electrical energy around the incandescent electrodes will produce sufficient heating on the inner walls of the pole chambers. The effect of this improvement is further enhanced by the screening flanges 3 and 4. As a result of these two 15 measures, condensation of the mercury inside the 20 pole chambers is prevented. The internal diameter of the arc tube 2 is made as large as possible to ensure that the arc is kept away from the walls of the arc tube, limited however to a certain extent as otherwise the arc becomes unstable in 25 operation. It is also important to fix the dimensions of the arc tube so that the coldest spot

therein is maintained at such a temperature so as to produce a vapor pressure in excess of five atmospheres. For instance high pressure mercury vapor tubes, according to the illustration have proved satisfactory with an internal diameter of 8 mm., a wall thickness of 1.5 mm. and a distance between electrodes of 40 mm., operating with a voltage drop of about 26 volts/cm. and a current load of 1.0 ampere. The wattage is about 100 watt.

In some cases it is advantageous to use electrodes heated by external means. In this event, a further fusion lead is required and this can be provided by using two thin metal foils of about equal thickness, one as the lead-in for the current and the other for the heating of the electrode.

What I claim is:

A lead-in conductor for conducting currents of up to 10 amperes to high pressure mercury vapor tubes made of quartz and having solid end portions comprising a strip metal foil having its ends folded back and wires connected to said foil by passing between the layers of the folded backends of the foil, the foil including at least a portion of the folds embedded in quartz.

FRANZ LAUSTER.

CERTIFICATE OF CORRECTION.

Patent No. 2,187,860.

January 23, 1940.

FRANZ LAUSTER.

It is hereby certified that error appears in the above numbered patent requiring correction as follows: In the heading to the printed specification, after line 5, insert --In Germany November 13, 1935--; and that the said Letters Patent should be read with this correction therein that the same may conform to the record of the case in the Patent Office.

Signed and sealed this 14th day of May, A. D. 1940.

(Seal)

Henry Van Arsdale,
Acting Commissioner of Patents.
